[57] CLAIM

The ornamental design for a modular digital voice processing machine for recording voice and data, as shown and described.

DESCRIPTION

FIG. 1 is a reduced top front and left side perspective view of a modular digital voice processing machine for recording voice and data;

FIG. 2 is a front elevational view thereof;

FIG. 3 is a top plan view thereof;

FIG. 4 is a right side elevational view thereof;

FIG. 5 is a left side elevational view thereof; and,

FIG. 6 is a rear elevational view thereof.

FIG. I

FIG. 2

FIG. 3

FIG. 4**FIG. 5**

FIG. 6
